DESIGN FOR A PRESCRIPTION SPOON

John Orenstein, Minneapolis, Minn.

Application June 14, 1945, Serial No. 120,093

Term of patent 14 years

(Cl. D52—1)

To all whom it may concern:

Be it known that I, John Orenstein, a citizen of the United States and residing in the city of Minneapolis, Hennepin County, State of Minnesota, have invented a new, original, and ornamental Design for a Prescription Spoon, of which the following is a specification, reference being had to the accompanying drawing, forming a part thereof, wherein,

I claim:

The ornamental design for a prescription spoon, as shown.

JOHN ORENSTEIN.
